UNITED STATES PATENT OFFICE.

WILLIAM W. LEE, OF NORTHAMPTON, MASSACHUSETTS.

DESIGN FOR A TABLE-KNIFE.

SPECIFICATION forming part of Design No. 21,180, dated November 24, 1891.

Application filed June 13, 1891. Serial No. 396,192. Term of patent 14 years.

To all whom it may concern:

Be it known that I, WILLIAM WILSON LEE, of Northampton, in the county of Hampshire and State of Massachusetts, have invented and produced a new and original Design for Knives Formed with Bolsters, of which the following is a specification, reference being had to the accompanying drawings, forming part thereof.

10 Figure 1 is a view of the side of a table-knife, and Fig. 2 an edge view thereof, these two views being deemed essential to illustrate my design.

15 My design consists in two recesses in opposite edges of the blade on the blade side of the bolster, which has its edge or periphery rounded from side to side, whereby a new, useful, and original shape of these articles of manufacture is produced.

20 In the drawings, a is the handle, a' the bolster, and a^2 the blade. The blade has an in-

dentation b on its back edge near the bolster a' on the blade side thereof and a corresponding indentation b' on its cutting or front edge, thus producing a knife of a new, distinct, and pleasing appearance. 25

A knife containing my design is shown in my application, Serial No. 396,130, of even date for a mechanical patent.

What I claim is—

The design for knives having bolsters herein shown and described, the same consisting of the indentations b b' on opposite edges of the blade on the blade side of the bolster and contiguous to the bolster, the periphery 35 or edge of which is rounded from side to side, as shown.

WILLIAM W. LEE.
